Inventor

WILBUR FISH BARTHOLOMEW

By his Attorney

W. F. Bartholomew

UNITED STATES PATENT OFFICE.

WILBUR FISK BARTHOLOMEW, OF BROOKLYN, NEW YORK.

DATE AND RUBBER-TYPE HOLDER.

1,277,027.

Specification of Letters Patent. Patented Aug. 27, 1918.

Application filed January 17, 1918. Serial No. 212,209.

To all whom it may concern:

Be it known that I, WILBUR FISK BARTHOLOMEW, a citizen of the United States, and a resident of Brooklyn, in the county of Kings and State of New York, have invented certain new and useful Improvements in Date and Rubber-Type Holders, of which the following is a specification.

The invention pertains more particularly to stamps of the character commonly employed by hand, and resides more especially in a novel cushion adapted to receive dates, rubber type and the like, by means of which, when inked, impressions are made. Stamps of the character to which my invention pertains usually consist of a handle, a base or block of wood or the like secured thereto and a rubber cushion secured to said base or block and containing recesses into which the dating blocks and type are introduced, as required. When desired the cushion may also have some permanent characters delineated thereon, as, for illustration, the word "Received," whose use is convenient when the stamp is a dating stamp and the date characters are to be changed from day to day.

The object of my invention is to improve the cushion member of the stamp, and in doing so to remedy many objections which are known to exist in the cushions of stamps as heretofore constructed. One objection to the cushions of stamps as heretofore constructed is that after some use the type introduced into the recess thereof become loose or fail to retain their position, and attempts have been made to remedy this objection with the use of metal partition plates and the like. It has been found however that in many instances the means employed for improving the cushion has resulted in depriving the stamp and type of the desired cushioning effect, and one of the purposes of my invention is to so improve the cushion that it will very firmly hold the type and date members and at the same time afford thereto the proper cushioning effect, both at the sides and back thereof. My invention also increases the life of the cushion, especially about the recesses which receive the type and date members. In accordance with my invention the recesses in the cushion may

be of any desired outline and such recesses are usually oblong or rectangular, and in carrying out my invention I mold within 55 the rubber of the cushion and near the outer surface thereof a flat metal frame which will not project into the recesses of the cushion, but encompass said recesses and leave between its inner edge and the edges of the 60 recesses a sufficient body of rubber for closely engaging and cushioning the type or dates, such type or dates at their inner ends being seated upon a portion of the rubber of the cushion. The frames employed by me are preferably of thin flat metal and therefore are light and occupy the minimum space within the cushion and at the same time are capable of resisting lateral strain. Sometimes these rubber 70 stamps are used with rubber type arranged in various ways to spell words and at other times they are used with date blocks which bear abbreviations for the months of the year, a block for the year, as "1918," and 75 blocks on which are formed numerals defining the days of the month. These dates may be classed as type, and therefore in this application I use the word "type" to denote the type bearing the letters of the 80 alphabet as well as blocks bearing data for the dates it may be desired to employ in the stamp.

The invention will be fully understood from the detailed description hereinafter 85 presented, reference being had to the accompanying drawings, in which:

Figure 1 is a bottom view of a hand stamp embodying my invention;

Fig. 2 is a vertical section, partly broken away, through the same, taken on the dotted line 2-2 of Fig. 1;

Fig. 3 is a horizontal section through a portion of the cushion of the stamp taken on the line of the metal frame which, in accordance with my invention, I mold within 95 said cushion to encompass the type receiving recess therein;

Fig. 4 is a bottom view, partly broken away, of the cushion of a stamp, said cushion 100 having an oblong recess for the type and an elongated frame encompassing the said recess;

Fig. 5 is a sectional view through the

same, taken about on the line of the embedded frame or about on the line 5—5 of Fig. 6, and Fig. 6 is a vertical section through the cushion of Fig. 4 and taken 5 about on the dotted line 6—6 of Fig. 4.

In the drawings, referring to Figs. 1, 2 and 3, 10 designates the rubber cushion, 11 the base block, and 12 the handle, the base block and handle being of any suitable character and the cushion 10 being of customary character with the exception of embodying 10 my present invention. The cushion 10 is shown as formed with a substantially rectangular recess 13 for the type 14, and the 15 type 14 will bear any suitable characters and be of a size to snugly fit the recess 13. The type 14 are detachable from the recess 13 and other type may be substituted therefor, as is required in dating stamps. The 20 cushion 10 may be formed with permanent type characters 15, when desired.

Within the cushion 10 is embedded a frame of metal or equivalent rigid material 16, this frame being preferably of flat sheet 25 metal of greater width than thickness in cross-section. The frame 16 is molded within the rubber of the cushion 10 and, as shown in Figs. 1 and 2, encompasses the recess 13, the inner edge of the frame being close to 30 the corners of the recess 13, but separated from the sides and ends of said recess so as to leave substantial portions 17 of the rubber about the sides and ends of the recess, these portions 17 serving to aid in 35 cushioning the type. The frame 16 is adjacent to the outer end of the recess 13, this being the portion of the cushion most likely to become distorted and weakened by the application to and removal of the type from 40 said recess. The frame 16 may be in the shape of a ring, as shown in Fig. 3, and it will vary in outline in accordance with the outline of the recess intended to receive the type.

45 In Figs. 4, 5, and 6 I number the rubber cushion 18, and this cushion 18 is formed with an elongated recess 19 to receive the type 20. The elongated recess 19 is made use of when a straight line impression is 50 desired, whereas the rectangular recess 13 is made use of when the impression is to be in several lines or of what is called pyramid character, as shown in Fig. 1. The recess 19 does not extend entirely through 55 the cushion 18, sufficient rubber being left at the inner end of the recess to form a cushion 21 for the inner ends of the type. Within the rubber of the cushion 18 and encompassing the recess 19 is embedded a 60 frame 22 which, except for its outline, is the same as the frame 16 hereinbefore referred to and employed for a like purpose and affording like results.

In both forms of the invention shown, the frame embedded within the rubber cushion 65 and encompassing the recess therein, performs the important duty of strengthening the cushion at the points where ordinarily the cushion is strained by the application to and removal of the type therefrom and 70 by the compression of the type during the use of the stamp, and said frame performs this duty without depriving the sides and ends of the recess of the cushioning effect so necessary for the type and for the successful use of the stamp.

I do not limit my invention to a cushion having any special shape of recess to receive the type, since obviously such recess must vary in accordance with the character and 80 size of type to be inserted therein. I illustrate two forms of recesses as illustrative of my invention without intending to limit the invention to any special form of recess. My invention resides in the embedded frame 85 encompassing the recess without interfering with the provision of cushioned opposite walls for the recess, whereby the type introduced into the recess become properly cushioned and are rendered effective regardless of the presence of my metal frame or 90 ring. It is to be noted also that the metal frame is very much less in thickness than the depth of the recess it encompasses and therefore does not deprive the type of the 95 benefit of the cushion throughout any portion of their length.

What I claim as my invention and desire to secure by Letters Patent, is:

1. A stamp comprising a base, an elastic 100 cushion thereon containing a recess for type and the like, and a frame embedded in said cushion and encompassing said recess outwardly from the walls thereof and being less in thickness than the depth of said recess.

2. A stamp comprising a base, an elastic cushion thereon containing a recess for type and the like, and a frame embedded in said cushion and encompassing said recess adjacent to the outer end thereof and being positioned outwardly from the walls of said recess, leaving said recess with cushioned walls.

3. A stamp comprising a base, an elastic 115 cushion thereon containing a recess for type and the like, and a thin sheet metal frame embedded in said cushion and encompassing said recess outwardly from the walls thereof.

4. A stamp comprising a base, an elastic 120 cushion thereon containing a recess for type and the like, and a metal frame encompassing said recess outwardly from the walls thereof and being materially less in thickness than the depth of said recess, leaving 125 said recess with cushioned walls.

5. A stamp comprising an elastic cushion containing a recess for type and the like, and a rigid frame embedded in said cushion and encompassing said recess outwardly
5 from opposite walls thereof and being materially less in thickness than the depth of said recess.

Signed at New York city, in the county of New York and State of New York, this 16th day of January, A. D. 1918.

WILBUR FISK BARTHOLOMEW.
